CLAIM

The ornamental design for a flood sensor, as shown and described.

DESCRIPTION

FIG. 1 is a bottom front perspective view of an embodiment of a flood sensor showing our new design;

FIG. 2 is a back view thereof;

FIG. 3 is a front view thereof;

FIG. 4 is a right side view thereof;

FIG. 5 is a left side view thereof;

FIG. 6 is a top view thereof;

FIG. 7 is a bottom view thereof;

FIG. 8 is a bottom front perspective view of another embodiment of a flood sensor showing our new design;

FIG. 9 is a back view thereof;

FIG. 10 is a front view thereof;

FIG. 11 is a right side view thereof;

FIG. 12 is a left side view thereof;

FIG. 13 is a top view thereof; and,

FIG. 14 is a bottom view thereof.

The broken lines in the drawings of the flood sensor or the parts and/or portions thereof are for environmental purposes only and form no part of the claimed design. The shade lines in the drawings show contour and not surface ornamentation.
